C. B. HUTCHINSON, OF AUBURN, NEW YORK.

Letters Patent No. 63,052, dated March 19, 1867.

IMPROVEMENT IN MACHINES FOR SETTING STAVES IN BARRELS.

The Schedule referred to in these Letters Patent and making part of the same.

TO ALL WHOM IT MAY CONCERN:

Be it known that I, C. B. HUTCHINSON, of Auburn, in the county of Cayuga, and State of New York, have invented a new and improved Device for Setting up Barrels, Casks, &c.; and that the following description, taken in connection with the accompanying drawings hereinafter referred to, forms a full and exact specification of the same, wherein I have set forth the nature and principles of my said improvements, by which my invention may be distinguished from all others of a similar class, together with such parts as I claim and desire to have secured to me by Letters Patent.

This invention relates to a new and improved device for setting up barrels, casks, &c., whereby the staves previously chamfered and crozed may be set up around their own head, the use of truss hoops avoided or rendered unnecessary, the barrels or casks can be made of different sizes, and the work performed expeditiously and in a perfect manner. In the accompanying sheet of drawings—

Figure 1 is a side elevation of my invention partly in section.

Figure 2, a plan or top view of the same.

Figure 3, a side elevation of a modification of the same.

Similar letters of reference indicate corresponding parts.

A represents a base-plate in which a vertical stand or column B is secured, and on the top of the latter there is a horizontal circular plate or table D, the upper surface of which is made concave or in disk form, and is encompassed by a metal band, E, which is bevelled at its upper edge to suit the bevel of the barrel-head of different sizes designed to rest upon it. On the stand or column B, directly underneath the plate or table D, there is a circular plate or band, C, the outer edge of which is for the staves to rest against in the setting up of the cask or barrel. These plates are fitted on the stand or column with a screw-thread or with set-screws, so that they may be readily adjusted higher or lower on the stand or column, as the length of the staves or the size of the cask or barrel may require. F represents a clamp, composed of three tubular arms, b, which extend radially from a central hollow hub, c, having a screw, G, passing centrally and vertically into it. This screw G works in a head, d, within the hub c, (see fig. 1,) and said head is connected by links e with rods f placed one within each arm b. The screw G works in an internal thread in the top of the hub c. The arms b are provided at their outer ends with a jaw, g, and these jaws may be adjusted further in or out by means of set-screws, h, as will be fully understood by referring to figure 1, and it will further be seen, by referring to this figure, that by screwing down the screw G, the rods f will be forced outward and a hoop, H, clamped firmly between the ends of the rods f and the jaws g. The arms b are each provided with a pendent projection or foot, h', the use of which will be presently seen.

The device is used as follows: One of the heads I of the barrel or cask to be set up is placed on the plate D, and rests upon the upper edge of the metal band E, the bevel of the head being on the latter, as shown in fig. 1. The hoop H, which is a chine hoop, is then secured in the clamp F, and the latter placed on the head I. The staves J, previously bent in bilge form, then jointed, chamfered, and crozed, are then inserted at one end between the edge of the head I and the chine hoop H, and drop in and rest against the circular plate C, the staves being all set up around the head, the edge of the latter being in the crozes i of the staves. The staves, as thus set up, are allowed to hang freely, and when all are thus adjusted the quarter hoop may be placed on or over the staves, the latter being adjusted in position. The chine hoop may then be detached from the clamp, and the latter pressed down and then the bilge hoop put on. One-half of the hoops are now adjusted on the barrel or cask, and the latter removed from the device, inverted, and the remaining hoops put on and the other head adjusted in the cask or barrel. In fig. 2 is shown a modification of the device. Instead of the skeleton frame, as shown in fig. 1, a cast-iron or wooden shell, K, is shown, provided with a base, L, and having a metal cap, M, on its upper end on which the barrel or cask-head is placed. Instead, also, of the plate C, which serves as a gauge for the staves when the same are pressed inward to have the hoops adjusted upon them, an external hoop, N, is shown, which answers the same purpose, the hoop N being adjusted higher or lower and secured in position by set-screws, i*. The shell K may also be adjusted higher or lower and secured in position by set-screws j. This adjustment is necessary in order to compensate for staves of greater or less length. In the plan shown in fig. 1, the plates C and D are screwed higher or lower on the stand or column B to obtain the

same end. In adjusting the staves to the head and bringing the former in proper position, the lower ends of the staves rest upon the base.

It will be seen from the above description that barrels may be set up with the greatest facility and expedition. The work is all done at once and with the least manipulation possible. The barrels or casks will all be of the same dimensions, as the staves are fitted to the heads instead of the heads being fitted in the staves, and if the heads be of the same diameter the capacity of the barrels or casks will be the same. A variation in the length of the staves will of course make some difference in the capacity of a barrel or cask, but trifling compared with a variation in the diameter of the heads, but in this case, as the staves are all previously prepared by machinery, they of course will be of uniform length.

Having thus described my invention, I claim as new, and desire to secure by Letters Patent—

1. The setting up of barrels, casks, &c., by suspending the chine hoop by means of a clamp, or its equivalent, in such relation with the head, which is placed on a suitable frame or support, that the ends of the staves may be inserted between the head and chine hoop, substantially as shown and described.
2. The adjustable table D, constructed with a concave upper surface and of a diameter smaller than that of the barrel, for the purpose described substantially as specified.
3. The combination of the clamp, frame, or support, and gauge, when arranged substantially as and for the purpose set forth.

C. B. HUTCHINSON.
